Inventor

G. E. Rutledge

UNITED STATES PATENT OFFICE.

G. E. RUTLEDGE, OF DAYTON, OHIO.

IMPROVEMENT IN PAPER-MAKING MACHINERY.

Specification forming part of Letters Patent No. 38,698, dated May 26, 1833; antedated November 21, 1861.

To all whom it may concern:

Be it known that I, G. E. RUTLEDGE, of Dayton, in the county of Montgomery and State of Ohio, have invented a new and useful Improvement in Paper-Making Machinery; and I hereby declare that the following is a full, clear, and exact description of the same, reference being had to the accompanying drawings and letters of reference marked thereon, which form part of this specification.

My invention is confined to the pulp-vat, and has for its object the production of a paper wherein the fibers are so thoroughly crossed and felted together as to render the web or tissue equally strong in all directions.

In the complete continuous system of machinery for paper-making invented by Fourdrinier my improvement is not applicable, nor is it required, the paper made by that apparatus being of such a quality, so far as the disposition of the fibers is concerned, and the consequent equal tenacity of the tissue in all directions, as to leave little to be desired; but the machinery of Fourdrinier is expensive, and consequently not used by manufacturers of small capital.

In the commonly-used and comparatively inexpensive apparatus to which my improvement is applicable a sieve-cylinder is made to revolve in the pulp-vat. The level of the water within the cylinder being maintained by a discharge-pipe at a lower altitude than that of the pulp in the vat, a pressure is thus exerted by the pulp outside the cylinder, causing the water to drain through the meshes of the wire-gauze, and the fibrous portion of the pulp to adhere on the outside of the same. As the sieve-cylinder revolves, the web of incipient paper is carried therefrom by contiguous moving web of felt, &c., as is well understood by those skilled in and conversant with the art of paper-making.

It will be evident, on a short consideration, that the revolution of the sieve-cylinder in the still liquid pulp of the vat will have a tendency to draw or "comb" the suspended fibers into a direction longitudinal to the revolution of the cylinder. The web of paper thus formed on the cylinder may be expected, therefore, to possess less tenacity in a longitudinal than in a transverse direction, and this is found, in fact, to be the case, a quick eye being able

even to detect in unsized paper thus made the longitudinal arrangement of the fibers.

Now, my invention relates to the neutralization of this action of the revolving cylinder to arrange the fibers parallel to each other in a longitudinal direction; and it consists in the establishment of a current in the liquid pulp in the direction of rotation of sieve-cylinder, and of about equal velocity therewith, by means of a pair of revolving corrugated or paddle cylinders and auxiliary partitions arranged in the pulp-vat, the axes of said cylinders being parallel to the axis of sieve-cylinder. These paddle-cylinders, being set in motion, tend to produce a current in the liquid pulp in the direction of the revolution of the sieve-cylinder, and of about equal velocity therewith, so as to render the periphery of said sieve cylinder and liquid pulp surrounding it virtually at rest relative to each other. Thus, the fibers in suspension in the water are left in the best condition for felting, lying in all directions, and the web adhering to the sieve-cylinder is found more equally felted together, and possesses greater uniformity of strength in all directions.

In order that others duly skilled may be enabled to understand and construct and use my invention, I shall proceed to describe it in detail.

In the accompanying drawings, Figure 1 is a perspective view of the pulp-vat and contained cylinders, including my improvement. Fig. 2 is a longitudinal vertical section of the same.

Like letters of reference designate like parts in all the drawings.

A is the pulp-vat, and *a* is the curved secondary floor of the same.

B is the sieve-cylinder, on which the paper is formed. As, however, this cylinder is of common construction, I shall not further describe it.

b is the outlet from the inside of cylinder B, by which the water, &c., which percolates through the meshes of the wire-gauze covering is let off, the level within the cylinder being kept lower than that without the same, so as to obtain a certain amount of hydrostatic pressure from the outside, or, as it is more commonly expressed, to get suction through the sieve-cylinder.

C C are two corrugated or paddle cylinders, revolving in suitable stuffing-boxes in sides of

pulp-vat, placed with their axes parallel to the axis of sieve-cylinder, and their corrugations or paddles gearing or meshing into each other. The floor *a* is fitted around the outer circumference of cylinder *C'*, and a concave, *e*, is thrown across the vat and curved to fit the circumference of cylinder *C*. A diaphragm, *d*, curved in a direction parallel, or nearly so, to the sieve-cylinder *B*, together with the partitions *e* and *f*, completes the arrangement for securing the currents mentioned in the introduction to this specification.

X is a pulley on shaft of cylinder *C*, for receiving a belt from any prime mover, and by means of cogged pinions *x x'* the cylinder *C'* is put in corresponding motion thereby. The sieve-cylinder is put in motion by another cylinder resting on top, having felt-web for carrying off the paper passing around. As, however, this forms no part of my invention, I refrain from describing it further or representing it in the drawings.

The operation of my invention is as follows: The sieve-cylinder *B* being put in revolving motion in the direction of the arrows, and the corrugated cylinders *C C'* being likewise put in motion in the direction of the arrows thereon marked, the pulp in the vat *A* will be put into motion, and two currents will be formed, the one above the diaphragm *d*, in the direction of the revolution of sieve-cylinder, as shown by the arrows, and the other beneath said diaphragm, in the opposite direction, toward the revolving cylinders *C C'*, as shown likewise by arrows. By adjusting the relative sizes of pulleys and driving-wheels the velocity of movement in cylinders *C C'* may be so controlled as to cause the currents in pulp-vat to be about equal in velocity to the movement of the periphery of sieve-cylinder *B*, and thus

the said periphery of sieve-cylinder will be relatively at rest in the fluid pulp. The result of this arrangement and operation will be, as already explained in the introduction, that the fibers are deposited on the surface of sieve-cylinder, lying in all directions, and thoroughly felted together, forming a paper, when pressed and dried, which is equally strong in any direction.

The advantages of my invention have already been, in part, set forth, but I shall here recapitulate and show the further advantages. With my improvement pulp may be used with longer fiber, and consequently pulp which has been submitted for a shorter time to the comminuting and disintegrating process. The cylinder *B* may likewise be run with less "suction" or pressure, thus allowing it to revolve with less friction from the felt packing, and consequently with less wear. Further, with less pressure and a longer fiber in the pulp there will be less loss of the "flour" of pulp than by the present apparatus. Finally, as before stated, the paper produced will be equally strong in one direction as in another.

Having now described the several parts and operation and object of my invention, together with its advantages, I proceed to state what I claim as new and desire by Letters Patent to secure:

Causing a current in that portion of the fluid pulp in which sieve-cylinder *B* rotates in a direction corresponding therewith, by which the periphery of the cylinder and the fluid pulp in which it rotates are relatively at rest, for the purpose herein set forth.

G. E. RUTLEDGE.
